UNITED STATES PATENT OFFICE.

CHARLES R. MABEE, OF TOLEDO, OHIO.

ART OF TREATING LIQUID SUBSTANCES.

1,420,646.

Specification of Letters Patent. Patented June 27, 1922.

Application filed July 19, 1915. Serial No. 40,757.

To all whom it may concern:

Be it known that I, CHARLES R. MABEE, a citizen of the United States, residing at Toledo, in the county of Lucas and State of Ohio, have invented certain new and useful Improvements in the Art of Treating Liquid Substances, of which the following is a specification, reference being had therein to the accompanying drawing.

- 10 The invention relates to the method of treating fluids or substances containing fluid to change their consistency, more particularly by causing an evaporation of the fluids.
- 15 Heretofore, there have been numerous evaporating systems and methods proposed, but as far as now advised, the system which has been more largely employed, especially in the milk industry, is that known as the
- 20 "vacuum system." Such a system entails the reduction of the atmospheric pressure on the material, requires a large amount of water for condensing purposes, much time is required for desired evaporation to proper
- 25 condensation, and it is generally recognized as necessitating an expensive equipment.

It has also been the practice to treat substances to evaporate the liquid therefrom by placing the material in bulk or in mass in a heated container and to stir or agitate the material and cause it to alternately move into contact with and away from the heated surface. The action may be designated as the stirring action. In this type of apparatus, scrapers have been employed which remove the material bodily from the surface toward the center.

All methods heretofore proposed, as far as I am now advised, are expensive and slow in operation. The present method is one wherein many of the objections found in the prior practices are avoided, the material is treated very rapidly; a very high temperature may be safely employed, the fluid or liquid is evaporated in whole or in part from the material economically and may be stated as one comprising generally the employment of the steps wherein the material to be treated is generated into a thin strata or layer in proximity to a treating surface, having a different temperature from that of the material, projecting the strata or layer rapidly over the surface, and permitting the vapors to escape without substantial impedance during the maintained continuity of movement of the material. The invention

comprehends also, the treatment of the surface during the continuity of movement of the material thereover, in a manner to prevent any substantial or detrimental interruption to heat transference or continued movement of the material.

The invention may be further definitely characterized as one wherein a relatively shallow body of material in liquid form or material containing a liquid, is maintained in a substantially concave form, moved rapidly over a heated surface of substantially circular section, while being subjected to the action of centrifugal force which maintains the substance in active proximity to the treating surface and at the same time maintains a free space into which the generated vapors or gases readily pass and escape.

In the hereinafter selected, illustrative method, reference is made to its employment in connection with milk, although in this particular it is to be understood that the invention is useful for evaporating fluid, either in whole or in part, from other substances. Milk is referred to in these specifications, not with a view of limiting the use of the invention, but more particularly with a view of designating a special substance which requires delicate treatment and for which the use of the invention is well adapted.

In carrying out the art or method, numerous forms of apparatus may be employed, but for the purpose of these specifications, an apparatus is shown and described which has been ascertained to be useful in demonstrating the utility of the method.

In the drawings:

Figure 1 is a longitudinal section taken through the apparatus, showing parts in elevation;

Figure 2 is an end view looking from the left of Figure 1;

Figure 3 is a cross section on the line 3—3 of Figure 1;

Figure 4 is a fragmentary section through a modified form of conveyor blade,

Figure 5 is a detailed fragmentary view of the outlet port, and,

Figures 6 and 7 are cross and longitudinal sections respectively, of a modified form of apparatus.

With reference to the drawings, 1—1 designate suitable standards, adapted to support the stationary parts of the machine. 2

designates a treating drum or receiving member of cylindrical cross section, which may be of a diameter from three to six feet, and is surrounded by a jacket 3. The ends 5 of the drum are partially closed, conveniently by end plates or caps 4, 5, both of which are provided with openings therein, conveniently above the center, as indicated at 4^a and 4^b. The opening 4^a may be closed 10 by a removable cap 4^c, having a sight opening 4^d therein. Communicating with the opening 4^b, is a vapor outlet pipe 6, the same being shown as broken away at its upper end, and is designed as hereinafter explained, to project the vapors away from the 15 machine. On the inner walls of the end plates 4, 5, are flanges 7, 7^a, having their innermost edges turned outwardly as shown, for purposes presently to be described. 8, 20 8^a, represent standards, located at opposite ends of the machine and provided at their upper ends with bearings in which a horizontal shaft 9 is mounted for rotation. This shaft 9 extends through the end plates and 25 treating drum, suitable stuffing boxes being provided, if desirable. One end of the shaft 9 carries a driving pulley 9^a, over which a belt 9^b passes, from a large driving pulley 9^c, driven by any suitable power for rapidly 30 driving the shaft.

Mounted on the shaft 9, adjacent the opposite ends of the treating drum, and adapted to rotate therewith, are radiating carrier arms 10, 10^a, each of which is conveniently 35 formed with outstanding peripheral flanges 10^b positioned adjacent the wall of the drum. Fixedly secured to the flanges 10^b of the carrier arms are longitudinally disposed metal angle bars 11, the outer or radial flanges of which lie in close proximity 40 to the wall of the cylindrical drum. These bars 11 extend from end to end of the treating drum. Seated on the angle bars, conveniently in a manner to permit a slight outward movement, are strips 12, the same being loosely held to the angle bars 11 by two bolts 12^a fixed in the strips and loosely passing through perforations in the angle bars. This permits a relative movement 45 between the bars and strips, as shown somewhat exaggerated in Figure 1 of the drawings, as but a very slight movement is necessary. Secured to the strips 12, are a series 50 of brushes 13, having their tufts formed conveniently of fibre, arranged to contact under centrifugal force with the walls of the cylindrical drum. The brushes are, by preference, extended the entire length of the strips, to wipe over the entire treating surface 55 of the drum; and maintain the same in proper polished condition. The yielding nature of the wipers or brushes is important as they do not wear or mar the surface of the container. However, other material 60 than fibre may be employed.

The movable part of the structure thus far described is properly characterized as a conveyor, and the entire operating part of the structure is positioned, as will be observed, closely adjacent the wall of the treating drum. The space between the two oppositely positioned conveyor members is unoccupied, as will be observed, for purposes presently to be stated. Entering the treating drum, conveniently through one of the end caps, is the supply tube 14 having its discharge end curved in the direction of the movement of the liquid being treated, the same being provided with a regulating valve 14^a varying the amount of material 70 entering the container. The exit end of the supply tube terminates adjacent the end wall within the plane of the flange 7 so that the milk, when the machine is used therewith, will be conducted into the zone of operation. 80

Located at any convenient point at the extreme opposite end of the treating drum, is a tangentially arranged outlet opening 15, the tangent being in the direction of movement of the material so that the natural 90 tendency of the material as it reaches this opening will be to escape therethrough. With this opening, a valved discharge conduit 16 communicates for leading the treated material to any desired place of deposit. 95 The valve may, however, be omitted.

Any suitable means for exteriorly heating the treating drum may be employed, but in the drawings is shown a valved steam supply, represented as a main supply pipe 17, 100 provided with a plurality of branch pipes 17^a leading through the wall of the jacket 3 at the top. The main pipe 17 is conveniently provided with the pressure regulator 17^b, diagrammatically shown, so that a constant high pressure may be maintained in the steam jacket. A temperature in excess of 211° F. can be employed successfully in treating milk without injury to the product, in fact a temperature as high as 300° F., 110 has been so employed. The water of condensation is allowed to escape through a steam trap 17^c at the lower part of the jacket.

In treating certain materials, it is desirable to incorporate therewith steam, air, or other treating substance, and with this in view, the apparatus above described is provided conveniently in its opposite side walls with a series of tangential inlet openings 18, the inclination of the openings being in line 115 with the direction of movement of the conveyors. Each opening communicates with a supply pipe 19, leading from a suitable source, as for instance, a supply of steam, when steam is employed as the treating 120 agent. If air is employed, the pipe 19 will be coupled with a suitable air supply, conveniently under suitable pressure. It has been ascertained, however, that in the treatment of milk for condensation or evapo- 125

tion, an imperforate treating cylinder is advantageous, and such a structure is illustrated in Figure 4, wherein the treating cylinder wall 2^a is shown as imperforate. It has also been ascertained that in many cases the apparatus can be used effectively with the described brushes omitted, in which event the radial flanges of the angle bars 11^a may be carried in close proximity to the treating surface, as shown in Figure 4. In this construction the angle bars constitute the conveyors.

In treating substances containing a large percentage of fluid, it has been ascertained that the vapors entering the unoccupied space within the center of the treating drum will readily escape through the end openings, in which particular both of the openings in the ends of the apparatus may be left uncovered. However, it is desirable to remove the vapor, to a point somewhat remote from the machine, and for that purpose the conductor pipe 6 is employed, and with a view of projecting the vapor through the pipe rapidly, any convenient form of vapor propeller, such as the fan 20, may be used. This fan may be mounted on a shaft 21, supported in a depending bracket 21^a and having its end passed through an opening 30 in the curved side wall of the pipe 6. The end of the shaft 21 is provided with a small pulley 21^b which is belted to a driving pulley 21^c, keyed to the main shaft 9, as shown.

The machine can be used and the process practiced, as stated, by removing the cap for the opening in the left hand end plate, thus establishing a free circulation of air throughout the machine. The curved deflecting plates 7, 7^a, within the machine at the ends are useful in conducting to the brushes any material that may flow down the end caps or plates without material agitation.

It will be observed that the interior of the machine is perfectly smooth, presenting no obstruction to the free movement of the material, and this enables the material, especially if milk is employed in the machine, to move rapidly without impedance. By this means foaming is obviated and a disruption or breaking up of the film or layer is prevented. This is important in that it minimizes the danger of the entrainment of valuable constituents of the material and the passing thereof out of the machine with the vapors. It will be observed also that the wipers which are shown in the form of brushes in the present instance, are employed as wipers as distinguished from what is known in the art as "scrapers," the latter being employed to remove the entire bulk of the material from the surface and deposit it at different points free from the surface or proximity thereto. It has been ascertained that by the use of the brushes or

wipers a perfect continuity of action is maintained, and a concaved layer is formed and projected over the surface in substantial uniformity throughout the treatment. The surface is thereby kept in a polished condition so that very rapid heat transference is secured.

In Figures 6 and 7, there is shown a form of apparatus in longitudinal and cross section respectively, wherein the brushes or wipers are omitted. In the particular construction, while designed for the treatment of certain materials, as for instance tomatoes or other vegetables or fruit, brewers' slop and refuse from manufacturing plants, the steam jacket which is indicated at 20, has a supply 20^a and exhaust 20^b. The interior of the cylindrical drum is supplied with the material to be treated through the supply 21 having a control valve 21^a. The outlet for the treated material is located diagonally opposite the inlet, as at 22, and this outlet may be supplied with a valve 22^a, if desired. The cylinder is provided with a closed head 23 at one end and at the opposite end there is a head 23^a, provided with a nozzle 23^b, which may be carried to any suitable point of discharge. Surrounding the exhaust outlet and secured to the head 23^a is a deflecting flange 24, the purpose of which is to prevent the material from entering the discharge and for conducting the same down the end to a point where the material will be caught up by the rapidly revolving carriers. A shaft 25 is extended through the machine, being suitably mounted in the heads and provided with a pulley or other mechanism for driving the same. On the shaft at opposite ends are keyed spiders or arms 25^a which carry at their outer ends propelling or carrying blades 26. These are conveniently of L shape in cross section, their radial portions or flanges extending in proximity to the walls of the drum, as shown in Figure 7. The material introduced into the drum is caught up by the conveyors or carriers, projected onto the wall in layer formation and rapidly moved over the heated surface. The material gradually works its way to the far end of the cylinder and escapes through the discharge 22, by which time it has been properly treated. By operating the valve 21^a or valve 14^a the thickness of the material of the layer or film may be regulated and thus vary or regulate the degree of concentration of the material.

Of course it will be understood that as far as the apparatus is concerned, many widely different forms may be employed.

In carrying out the method with the apparatus above described, substantially the following may be regarded as the procedure. Assuming the material being treated is milk, the same is fed into the drum at one end

and in the direction of the flow, the conveyors having previously been set in motion are travelling at a high rate of speed (the speed may be altered according to the conditions) the material is immediately caught up by the conveyors and owing to the rapid movement thereof, in some instances estimated at 2800 feet per minute, is transferred to the highly heated treating surface of the drum and deposited thereover. The introduction of material is regulated by the valve and a deposit will be built up on the treating surface and throughout the area of the same, without impedance or interruption, very pronounced centrifugal action taking place and a very rapid movement of the deposit occurring, so that a constantly moving strata, layer or film of material, varying according to the supply, will be maintained on and move rapidly over the treating surface and endwise toward the discharge.

In practice, it has been ascertained that in the treatment of milk for condensing purposes, a film or layer of material from approximately one-eighth to one-half of an inch in thickness, may be very successfully employed, maintained or built up, and with great expedition, while in the treatment of certain other materials, the layer or film may be built up or increased in thickness from two to five inches, according to the density and consistency of the material operated upon.

It is also to be understood that the terms "layer" and "film" as used in these specifications and claims, are intended to define a relatively shallow deposit of material having, however, sufficient body to maintain under action its substantially uniform concaved or cylindrical formation.

The material is not allowed to settle in the treating drum or to leave the treating surface until the treatment has been completed, but on the contrary is maintained under constant movement and outward forcible centrifugal pressure toward and rapidly moved over the surface. As the material continues in its gyratory or circular movement and the treatment or evaporation of the liquid thereof continues, the vapors find free access into the quiet zone within the center of the treating drum and readily escape through the end openings.

The method by preference is continuous, the supply being maintained and the treated material being allowed to escape through the tangential opening 15. It has been observed that the movement of certain kinds of material in a circular course over the heated surface is somewhat likened to a thin layer having a substantially smooth interior surface, as distinguished from a broken-up or roughened surface. During the operation of the machine, the brushes

or wipers referred to are by centrifugal force carried outward against the surface, thereby maintaining the same in proper position. The conveyors are arranged conveniently in such proximity to the surface of the drum, either when equipped with the brushes or otherwise formed, as to maintain the layer of liquid properly in proximity and cause the same to move rapidly over the surface. By this rapid relative movement, a very high temperature can safely be employed, thus expediting the treatment and improving the product.

The hot gases, vapors or lighter substances generated by heat transference, being lighter than the liquid treated, will in part pass therefrom and in part, as I now understand it, be squeezed or forced through the material by the pressure created by the centrifugal force, pass into the quiet zone at the center of the treating drum or cylinder, from which they escape or may be drawn. It has been observed, also that in treating certain materials, the action is accelerated somewhat by the introduction of a treating material through the wall of the treating surface, the material being acted upon may be further modified or changed in its consistency and character, as for instance by the introduction of neutralizing and other agents such as a lime solution. One of the important results acquired by the practice of the method is that of substantial elimination of the usual loss of valuable constituents by entrainment.

Illustrative of one of the advantages of the present method over the known and generally practiced "vacuum pan" system, it has been ascertained that material can be treated properly in approximately less than one tenth of the time usually employed in the old practice and at a very great saving of labor and operative cost. It has also been ascertained that the product of this method is of superior quality.

It is to be understood, as above stated, that a larger volume of liquid enters through the intake or supply valve than leaves through the outlet pipe, and therefore the valve in the intake pipe may be regulated in such a manner as to permit the product to pass through the outlet pipe only after it reaches its desired density. In each instance, however, it will be noted that the material is subjected to uniform treatment throughout the operation.

The process is designated as the "film" or "layer" treatment, and as such can be employed successfully for treating milk or other substances to change their conditions, as distinguished from the old process of "bulk" treatment.

The apparatus may be very successfully used and the method practiced for the production of what is now known as "Italian

paste", a material used for soup stock. It may also be used for the recovery of potash from the waste materials of sugar mills. The apparatus can also be employed for the 5 treatment of sewage.

The term "relative rapid movement" herein employed has reference to a positive driven movement over a heated surface as distinguished from a slow lagging movement when a rotary drum is employed, such as illustrated in the patent to Eduard Theisen No. 552455. The term "free escape" and similar terms herein employed with reference to the vapors entering the 10 quiet or central unoccupied space, has reference to a condition wherein the vapors freely and rapidly escape from the central zone bordered by the moving layer of material through a relatively large or copious outlet, and wherein evaporation may be readily and quickly effected and it is intended to distinguish the invention from such suggestions as are found in pasteurizers or apparatus for analogous purposes, such as shown 15 in the patent to Darius W. Payne No. 878997, and the Danish patents to Zeuthen and Larsen, Nos. 13,553, of August 22, 1910, 14,202, of February 6, 1911, and 14,889, of July 31, 1911, respectively.

30 In the substance to be treated there will be naturally a certain amount of material which is not evaporable under the treatment or constituents which are not so readily evaporable as others. Therefore when the terms 35 "equal, uniform or substantially equal and uniform distribution" are employed in this specification, they have reference to such non-evaporable or less readily evaporable constituent part of the material. It has 40 been ascertained that to produce a uniform product this equal, substantially equal or uniform distribution of said substance is desirable.

The apparatus herein described is claimed 45 in my copending application No. 77996 filed February 12, 1916. This application in so far as the subjects matter are in common is a continuation of my copending applications Serial No. 738178 filed December 23, 1912 50 and Serial No. 718114, filed August 31, 1912.

In my other applications, Serial Number 718,114, filed August 31, 1912 and Serial Number 738,178, filed December 23, 1912, I have shown how vacuum or suction ducts 55 and mechanisms of modified forms for lowering the pressure in and exhausting vapors and gases from the container can be applied. In treating some materials only partial vacuum is required for slight lowering of the 60 internal pressure below that of the atmosphere, this being however a matter of judgment and option as to how far the exhausting and vacuum shall be carried. The fan at 20 typifies any suitable apparatus of this 65 sort.

In some of my mechanisms I depend upon the heated vapors escaping from the interior through the end or ends of the container without exerting suction or similar force thereon from the outside, in such case merely permitting them to normally escape, as provided in my application Ser. No. 108,956, filed October 24, 1913; but under many circumstances it is better to positively withdraw the vapors or remove them by means 70 of agencies typified by those illustrated and described.

When the container is arranged as herein shown, that is, positioned with its axis horizontal, the material of the film travels horizontally, the vapor tending to move radially into the central open zone. As soon as it leaves the heated surface it begins to condense and the formation of globules of water commences. These can be lifted vertically, 80 but when large volumes of vapor are rapidly produced such condensed globules can, before they become heavy by condensation, be more readily carried outward horizontally, or on lines at angles to the vertical, from the 85 collecting zone, and thus be prevented from dropping again toward the heated surface to cause a waste of heat units in their re-vaporizing.

In addition to the copending applications 90 above referred to, cross-reference is made to the following copending applications illustrating and describing modified forms of evaporating and condensing apparatus or methods of procedure in the evaporation or 100 condensing of materials, and I reserve the right to claim in the said copending applications the novel subjects-matter therein disclosed and not herein claimed:—No. 277,904 (a division of No. 718,114), filed February 105 18, 1919; No. 805,598, filed December 9, 1913; No. 280,443 (originally No. 806,890), filed December 15, 1913; No. 358,433 (originally No. 806,888), filed December 15, 1913; and No. 366,962 (originally No. 806,889), 110 filed December 15, 1913.

Having thus described the invention, what is claimed is:

1. The art of treating substance containing an evaporable constituent consisting in 115 spreading the substance on the inner surface of a container rapidly moving the substance circularly over the inner surface of the container and causing the same to progress from the point of introduction to 120 a remote point of discharge, heating the inner wall of the container causing the vapors to move inwardly from the layer toward the center of the container and to escape therefrom and regulating the thickness of the 125 layer deposited on the heated wall of the container.

2. The method of treating substance containing liquid to change its consistency which comprises the introduction of the 130

substance into a heated container of circular cross section imparting to the substance so introduced the form of a concave layer, causing the layer to rapidly circulate over the 5 heated surface of the container, maintaining the layer formation of the substance during treatment, simultaneously positively maintaining the treating surface free from adhering accumulations and permitting the 10 generated vapors to escape from the substance during treatment and finally from the container.

3. The method of treating substance containing liquid to change its consistency 15 which comprises the introduction of the substance into a heated container of circular cross-section, imparting to the substance so introduced the form of a concaved layer of substantial uniformity, causing a rapid relative circulating movement between the 20 layer and heated surface, permitting the vapors to freely escape from the substance toward the center and from the container, and maintaining the heated surface free 25 from accumulations during the treatment.

4. The method of treating substance containing liquid to change its consistency which comprises introducing it into a horizontally disposed cylindrical container, 30 parting to the substance so introduced the form of a concave cylindrical sheet concentric with the container, maintaining said form of said sheet throughout the operation, simultaneously wiping the inner surface of 35 the container, imparting to the walls of the container a temperature different from that of the substance permitting the free escape of vapor from the material being treated and from the container.

40 5. The art of evaporation which consists in applying a layer of material under centrifugal force to the surface of a heated cylindrical container, subjecting said layer to continuous movement over said surface, 45 and independently of the material mechanically removing adhering material from said surface during said movement and maintaining within the center of the layer an open space into and from which vapor 50 may escape.

6. The art of treating liquid which consists in forming and maintaining a body of the liquid in layer formation while in contact with the inner surface of a heated 55 tubular container, subjecting said layer to continuous rotary movement under pressure relative to said surface, and independently of the material mechanically and yieldingly preventing the adherence of particles to the 60 surface without interrupting the rotatable movement of the layer body over said surface and maintaining within the layer an open space into and from which vapors may escape.

65 7. The art of treating a fluid substance to

remove evaporable constituents thereof consisting in shaping the substance in thin layer formation on the inner surface of a heated container of substantially circular cross section, causing the substance to move 70 lengthwise of the container from the point of introduction to the point of escape, permitting the vapors to freely escape or pass from the substance and from the container, and during the treatment without interrupting 75 the continuity thereof cleansing the surface of the container to maintain the same in a polished condition.

8. The art of treating a substance containing liquid for changing its consistency 80 consisting in introducing a volume of the substance tangentially into a treating container of circular cross-section, causing the material to assume the form of a thin layer on the treating surface, maintaining the 85 layer formation throughout treatment, rapidly moving the layer over the treated surface, heating the treating surface, permitting the gases and vapors to escape inwardly from the layer and to freely escape from the 90 container, and permitting the treated substance to escape tangentially.

9. The art of treating a substance containing liquid for changing its consistency consisting in introducing a volume of the 95 substance into a treating container of circular cross-section, positively causing the material to assume the form of a thin layer throughout the treating surface, maintaining the layer formation throughout treatment, rapidly moving the layer over the treated surface, heating the treating surface to a temperature above 211° F., permitting 100 the gases and vapors to escape inwardly from the layer and to freely escape from the 105 container.

10. The art of treating a substance containing liquid to change its consistency consisting in introducing the substance into a heated container of circular cross section 110 positively moving the substance circularly over the surface of the container permitting an amount of substance to enter the container sufficient only to form a spreading on the heated wall of the container, causing the 115 substance to move rapidly over the heated wall and to escape, permitting the vapors to pass from the substance inwardly and causing the vapors to escape from the container under accelerated movement.

11. The method of producing a condensed milk product consisting in introducing the milk into a container of circular cross section, heating the milk in said container to a temperature to which milk cannot be subjected even for relatively brief periods of 125 time without material injury to the constituents to vaporize a portion of the liquid thereof, shaping the milk in the form of a layer upon the surface of the container, 130

rapidly moving the layer circularly over the surface and simultaneously causing the entire body of milk to move from the point of introduction toward the opposite end of the container, and permitting the vapor to escape inwardly from the layer and freely from the container, the time of treatment being less than the brief period which would serve to injure the milk if exposed and held 10 in contact with the treating surface in the presence of a high degree of heat.

12. The art of treating a substance containing liquid to change its consistency consisting in subjecting the material or substance to a centrifugal action projecting it laterally and longitudinally and subjecting the substance to a temperature sufficiently high as to injuriously affect the constituents thereof when allowed to remain under the 15 influence of the temperature for a short period of time causing the material to depart from the heat and permitting the generated vapors to escape during the progress of the treatment.

13. The art of treating a substance containing liquid to change its consistency, consisting in subjecting the material or substance to the action of centrifugal force and to a temperature sufficiently high as to injuriously affect the constituents of the material if the same be allowed to remain under the influence of the temperature without moving for a short period of time, causing the material to move rapidly while under the 20 influence of the said high temperature and to depart from the influence of the temperature before the material is injuriously affected thereby.

14. The art of treating milk to reduce its liquidity consisting in subjecting a layer of the milk to a temperature at or above 212° F. by bringing the same centrifugally into contact with a heated surface causing the milk to move rapidly over the surface and to 45 escape from the surface before the high heat to which it has been subjected has injuriously affected the milk constituents.

15. The method of treating a substance containing liquid to change its consistency 50 by evaporating liquid therefrom consisting in spreading a layer of the substance on the heated wall of the container having a circular cross section, rapidly and positively circulating the substance as it enters the container, over the surface and crosswise thereof permitting the vapors and gases to escape inwardly from the layer and freely from the container and regulating the thickness of the layer by varying the amount of the substance 55 entering the container.

16. The process of concentrating a substance containing liquid consisting in introducing the substance into a container of substantially circular cross section heated to a 60 temperature sufficient to vaporize liquid con-

stituents of the substance at substantially atmospheric pressure, shaping the substance in a layer upon the interior surface of the container, rapidly moving the layer circularly over the surface and simultaneously causing the entire body of substance to move from the point of introduction toward the opposite end of the container, permitting the substance to escape after treatment, permitting the vapor to escape inwardly from the layer and freely from the container, and simultaneously wiping the inner surface of the container.

17. The process of concentrating a substance containing liquid consisting in introducing the substance into a container of substantially circular cross section heated to a temperature sufficient to vaporize liquid constituents of the substance at substantially atmospheric pressure, shaping the substance in a unitary layer of continuous exterior conformation and with an interior substantially unobstructed vapor zone, rapidly moving the layer circularly over the surface and simultaneously causing the entire body of substance to move from the point of introduction toward the opposite end of the container, permitting the substance to escape after treatment, permitting the vapor to escape inwardly from the layer and freely from the container, and wiping the surface of the container.

18. The process of concentrating a substance containing liquid consisting in introducing the substance into a container of substantially circular cross section heated to a temperature sufficient to vaporize liquid constituents of the substance at substantially atmospheric pressure, shaping the substance in a unitary layer of continuous exterior conformation and with an interior substantially unobstructed vapor zone, rapidly moving the layer circularly over the surface, simultaneously causing the entire body of substance to move from the point of introduction toward the opposite end of the container, permitting the substance to escape after treatment, permitting the vapor to escape inwardly from the layer and freely from the container, and mechanically removing the adhering particles from the surface of the container without interrupting the movement of the body of liquid.

19. The process of concentrating a substance containing liquid consisting in introducing the substance into a container of substantially circular cross section heated to a temperature sufficient to vaporize liquid constituents of the substance at substantially atmospheric pressure, shaping the substance in a unitary layer of continuous exterior conformation and with an interior substantially unobstructed vapor zone, rapidly moving the layer circularly over the surface, simultaneously causing the entire body of

substance to move from the point of introduction toward the opposite end of the container, permitting the substance to escape after treatment, permitting the vapor to escape inwardly from the layer and freely from the container, and simultaneously wiping the inner surface of the container.

20. The process of condensing milk consisting in introducing the milk into a container of substantially circular cross section heated to a temperature sufficient to vaporize liquid constituents of the milk at substantially atmospheric pressure, centrifugally causing the milk to move rotarily and longitudinally upon the interior surface of the container, and mechanically removing the adhering particles from the surface of the container without interrupting the movement of the body of milk.
- 20 21. The process of condensing milk consisting in introducing the milk into a container of substantially circular cross section heated to a temperature sufficient to vaporize liquid constituents of the milk at substantially atmospheric pressure, shaping the milk in a layer upon the interior surface of the container, rapidly moving the layer circularly over the surface and simultaneously causing the entire body of milk to move from the inlet toward the outlet from the container, permitting the vapor to escape inwardly from the layer and freely from the container, discharging the milk from the container in substantially the same succession as it was introduced into the container, and mechanically removing adhering particles from the surface of the container without interrupting the movement of the body of milk.
- 40 22. The process of condensing milk consisting in introducing the milk into a container heated to a temperature sufficient to vaporize liquid constituents of the milk at substantially atmospheric pressure, shaping the milk in a unitary layer of continuous exterior conformation upon the interior surface of the container, rapidly moving the layer circularly over the surface and simultaneously causing the entire body of milk to move from the point of introduction toward the opposite end of the container, permitting the milk to escape after treatment, permitting the vapor to escape inwardly from the layer and freely from the container, and mechanically removing the adhering particles from the surface of the container without interrupting the movement of the body of milk.
- 60 23. The method of producing a condensed product consisting in introducing the material into a container of circular cross section, heating the material in said container to vaporize a portion of the liquids thereof, shaping the material in the form of a continuous uniform layer upon the surface of

the container, rapidly and continuously moving the layer circularly in the same direction over the surface and simultaneously causing the entire body of material to move lengthwise in the same direction from the point of introduction toward the opposite end of the container, and creating a partial vacuum in the container during the operation.

24. The process of concentrating a substance containing liquid consisting in introducing the substance into a container of substantially circular cross section heated to a temperature sufficient to vaporize liquid constituents, of the substance, maintaining a pressure in the container less than atmospheric, shaping the substance in a unitary layer of continuous exterior conformation and with an interior substantially unobstructed vapor zone, rapidly moving the layer circularly over the surface, and simultaneously causing the entire body of substance to continuously move in the same direction from the point of introduction toward the opposite end of the container, permitting the substance to escape after treatment, and permitting the vapor to escape inwardly from the layer and freely from the container.

25. The process of condensing milk consisting in introducing the milk into a container of substantially circular cross section heated in a temperature sufficient to vaporize liquid constituents of the milk, maintaining a partial vacuum in the container, shaping the milk in a unitary layer of substantially continuous exterior conformation and with an interior vapor zone, rapidly moving the layer circularly over the surface and simultaneously causing the entire body of milk to move continuously in the same direction from the inlet towards the outlet of the container, permitting the milk to escape after treatment, and permitting the vapor to escape inwardly from the layer and freely from the container.

26. The method of concentrating a substance containing liquid consisting in introducing the substance into one end of a container of substantially circular cross section heated to a temperature sufficient to vaporize liquid constituents of the substance, maintaining a partial vacuum in the container, shaping the substance in a layer upon the interior surface of the container, rapidly moving the layer circularly over the surface and simultaneously causing the entire body of the substance to move from the point of introduction toward the opposite end of the container, permitting the substance to escape after treatment, and permitting the vapor to escape inwardly from the layer and to pass from the container.

27. The method of vaporizing a liquid containing substance, such as milk, which con-

sists in uniformly heating a tubular container, supplying adjacent one end of the container and causing the substance as supplied to form a thin cylindrical layer upon 5 the interior face of said container while maintaining the particles so composing said substance in substantially the same order of flow, maintaining said layer under the pressure of contacting conveyors, maintaining a 10 quiet vapor receiving space throughout the length of the substance-lined heated container and permitting the escape of vapor therefrom, maintaining a pressure less than atmospheric within the container, and with- 15 drawing the evaporated substance from the opposite end of the container.

28. The art of evaporation, which consists in subjecting a relatively shallow body of material while under continuous motion in a 20 circular path to the action of centrifugal force, while in contact with a relatively immovable heated surface of a cylindrical container, causing the entire body of the material to simultaneously move in the same 25 direction lengthwise towards the discharge end of the container, and at the same time retaining within the center of the shallow cylindrical body of moving material a free space into which the vapors or gases are al- 30 lowed to escape, and withdrawing the separated vapors in a direction at substantially right angles to the force of gravity.

29. The art of evaporation which consists in applying to the inner surface of an externally heated cylindrical container, an endless 35 layer of substance, and subjecting the same while in uniform layer formation to a continuous rapid circular movement over the surface while maintaining the same in contact with said surface under pressure, 40 simultaneously causing the entire body of substance to move continuously towards the outlet end of the container, maintaining a central quiet zone within the layer, and re- 45 moving the separated vapors from the zone.

30. The process of concentrating a substance containing liquid consisting in introducing the substance into one end of a container of substantially circular cross section 50 heated to a temperature sufficient to vaporize liquid constituents of the substance at a pressure less than atmospheric, shaping the substance in a unitary layer of continuous exterior conformation and with an interior sub- 55 substantially unobstructed vapor zone, rapidly moving the layer circularly over the surface and simultaneously causing the entire body of substance to continuously move in the same direction from the point of introduc- 60 tion toward the opposite end of the container, permitting the substance to escape after treatment, and permitting the vapor to escape inwardly from the layer and freely from the container.

65 31. The process of concentrating a sub-

stance containing liquid consisting in introducing the substance into a container of substantially circular cross section heated to a temperature sufficient to vaporize liquid constituents of the substance at less than atmospheric pressure, shaping the substance in a unitary layer of continuous exterior conformation and with an interior substantially unobstructed vapor zone, rapidly moving the layer circularly over the surface and simultaneously causing the entire body of substance to move from the point of introduction toward the opposite end of the container, permitting the substance to escape after treatment, and permitting the vapor to escape inwardly from the layer and freely from the container.

32. The method of evaporating liquid-containing substances such as milk, which consists in continuously introducing the substance within a highly heated tubular container, imparting active centrifugal force and rapid rotary motion to the substance in cylindrical layer formation, maintaining the heated wall of the container free from the adhesion of particles of the substance, allowing the substance to absorb heat, allowing the gases and vapors thereby created to pass through the layer of the substance into the zone surrounded by the layer of substance, permitting the treated substance to continuously escape, and permitting the vapors and gases to rapidly escape from said zone independently of the treated substance through a large escape opening.

33. The method of evaporating liquid-containing substances such as milk, which consists in continuously supplying the substance adjacent one end of a tubular container having a concave treating surface, subjecting said surface to high heat, imparting to the substance as introduced active centrifugal force and rotary motion to form the same into a cylindrical layer, causing said layer to move over and against the concave surface of the container and move lengthwise thereof, allowing the substance to absorb heat, allowing the gas or vapor thereby created to pass through and from the substance into a cylindrical zone bounded by the layer of substance, allowing the generated gases or vapors to escape without impedance from said zone, maintaining the concave surface of the container free from adhesions and in a highly polished condition, and allowing the substance to continuously escape from the container as treated.

34. The method of treating liquid-containing substances, whereby to condense the same, which consists in continuously introducing the substance into one end of a cylindrical container, applying centrifugal force and rapid rotary motion to the substance introduced to spread it in a uniform layer over the concave surface of the container and to

continuously move it circumferentially and lengthwise in layer formation over and against said concave surface, subjecting the treating surface to high heat, allowing the substance to absorb heat from said treating surface, maintaining the treating surface free from adhesions of the substance and in a polished condition, allowing accumulated gases as they form in the substance to pass through and from the same to a central zone bordered by said moving layer of substance,

allowing the gases to freely and continuously escape from the container, and allowing the residue of the substance to continuously escape from the container.
